United States Patent Office

Des. 191,101
Patented Aug. 15, 1961

191,101

VEHICLE CAB

Theodore Ornas, Jr., Charles B. McGrew, Jr., and Bela Bardos, Fort Wayne, Ind., assignors to International Harvester Company, Chicago, Ill., a corporation of New Jersey

Filed June 13, 1960, Ser. No. 60,938

Term of patent 7 years

(Cl. D14—3)

FIG. 1.

FIG. 2.

FIG. 3.

The portions shown in broken lines are for the purposes of illustration only.

We claim:

The ornamental design for a vehicle cab substantially as shown and described.
